FRANK J. OAKES

33rd Owen H. Spencer
Attorney

UNITED STATES PATENT OFFICE.

FRANK J. OAKES, OF INDIANAPOLIS, INDIANA.

INTERNAL-COMBUSTION ENGINE.

Application filed May 21, 1926. Serial No. 110,655.

My invention relates to internal-combustion engines of the four cycle type, and more particularly to automobile engines, the firing and gaseous control of which are actuated by spur gearing driven by the main engine shaft, usually known to those familiar with the art as the crank shaft; and consists substantially in the construction, combination and arrangement of parts hereinafter set forth and pointed out more particularly in the claims.

An object of my invention is to provide an efficient and simple means for lubricating and muffling the working noises of spur gearing or the equivalent, which actuates the firing and gaseous control of explosive engines, and more especially in connection with automotive engines.

It is an important object of my invention to incase the usual timing and ignition gears of such engine in an oil-tight housing and constantly introduce lubricating oil under pressure in said housing during operation of same, there being an escape valve provided to release such oil as the hydraulic pressure of same reaches a certain number of pounds per square inch.

It is a primary object of my invention to carry into practice, an engine of this class, lubricated in the above manner, in which the conventional engine gear housing is modified to serve as the oil-tight gear housing; in which the oil is supplied to said housing under pressure by conduit communication of same with the regular overflow of a standard force feed automobile engine lubricating pump; and in which the discharge of the escape valve is directed to the regular oil reservoir of such engine.

It is a further object of my invention to provide a mechanism of this class in which oil thus supplied under pressure to the regular engine gear housing, is introduced at the departing interceptions of the timing or ignition gears and emitted at the approaching interceptions thereof, by which the incidental pumping tendency of same is favorable to the natural movement of the oil pumped otherwise, thru said housing.

It is also an object of my invention to provide an invention of this class in which the oil escapement valve may be manually adjusted to allow the pressure introduced oil to escape from the timing gear housing at a

different pound pressure per square inch, 55 as desired, according to the requirements.

The above and other objects are attained by the structure illustrated in the accompanying drawings, in which: the figure is partly a front end elevation and partly a 60 fragmentary sectional view of a typical automobile engine, and serves to somewhat pictorially and somewhat diagrammatically represent the invention.

Similar characters of reference designate 65 similar parts thruout the several views. Referring to the figure, the numeral 1 designates the crank case or frame portion of a typical automobile explosive engine, with which my invention is embodied, and upon 70 the upper portion of which is formed a cylinder means 2. The cover 3 is secured over the upper termination of said cylinder means and serves as a typical cylinder head therefor. The engine shown is of the conventional "cast in block" type.

The crank shaft 4 is revolvably mounted in the crank case 1 by means of the journals 5, being held in this relation by the bearing cap means 6. Ordinary pistons 7 are slidably disposed within the cylinder means 2, in the usual way, and each of said pistons is connected to its respective crank arm 8, of the crank shaft 4, as will be understood by those familiar with the art.

Conventional poppet valve stems 9 are 85 slidably disposed in connection with the gaseous passages 10, which are integrally included as a part of the cylinder means 2.

The push rod guides 11 are carried by the 90 crank case 1 in regular alinement with the valve stems 9. The push rods 12 are slidably disposed within said push rod guides. The upper ends of said guides embrace the lower ends of the valve stems 9, respectively, in customary end-to-end relationship and the lower end of said push rod, rides on the cam 13 of the cam shaft 14, and is operated thereby.

The spring seats 15 are secured to the 100 lower portion of the valve stems 9 in encircling manner and the expansion coil springs 16 encircle said valve stems between said spring seat and the gaseous passages 10 in conventional working manner, and serves 105 to actuate said valve stem and push rod guide in opposition to the cam 13.

The cam shaft 14 is mounted in the crank

case 1 in the customary journal manner. Said cam shaft carries at the gear end of the engine the cam shaft gear 17, said gear being concentrically secured to said cam shaft, and serving to be rotated integrally therewith.

The rotation of said cam shaft is effected by said cam shaft gear which serves to mesh with the corresponding crank shaft gear 18 which is secured to the crank shaft 4 in the ordinary way. It is understood that the said cam shaft gear, having twice the number of teeth 19 as the crank shaft gear has teeth 20, is correspondingly geared down and adapted to rotate one revolution to two revolutions of said crank shaft gear, in accordance with the usual and known principles of four cycle combustion engines.

The electrical generator 21 mounted on the crank case 1, is driven by the accessory drive gear 22, which in turn is driven by the cam shaft gear 17 with which said accessory drive gear is disposed in meshed relation. The generator 21 is used to supply the electrical ignition current for the spark plugs 23, threaded thru the cylinder cover 3, so as to extend slightly into the cylinder means 2, by which arrangement said spark plugs serve as a firing means for the engine. It is understood, however, that a water pump such as is ordinarily used in cooling water cooled engines, may be driven by the accessory gear 22, in place of the generator 21; and that any other such auxiliary engine accessory may 35 be likewise driven.

A usual oil reservoir 24 is secured to the lower side of the crank case 1, serving as a lubricating oil container or reservoir for feeding the lubricating oil pump 25, as will 40 be understood.

I have provided an oil tight gear housing 26 which incases the gears 17, 18, and 22, allowing the customary clearances between the housing walls and said gears.

I have observed in different automotive combustion engines, the embodiment of force feed oil pumps of different styles, which comprise a somewhat auxiliary mechanism to the engine proper and operate by a normally moving part of such engine, usually the crank shaft or cam shaft. In instances where such arrangement is carried out, one such pump is usually provided to each engine in such a manner that during the normal operation of the mechanism as a whole, oil is pumped from an oil reservoir such as 24, thru tributaries to the various lubricated parts of the engine.

During the operation of the mechanism shown, oil is forced by means of the pump 25 to the lubricated parts of the engine. The inlet 27 of said pump is fed from the oil 28, held by the reservoir 24, said inlet being conveniently submerged in said oil. The outgo 65 of oil thus pumped is directed from said

pump by means of the outlet conduit 29, which extends to the crank shaft journals 5 and by tributaries 30, to the cam shaft bearings 31, as well as to other parts of the engine usually lubricated in such manner.

In most instances where force feed lubrication is used in connection with automotive engines, it is thought best to provide an oil pumping means of substantially greater capacity than would be actually required to supply oil for the particular lubricating purposes. I understand that this plan is adhered to, to make sure that the lubricated parts are at all times amply supplied with plenty of oil. It is very essential, however, when such plan is carried out, to provide in connection with the outlet of the oil pump, an overflow, or surplus flow to allow a somewhat restricted means of releasing the over supply of oil thus pumped, and directing 85 same back to the oil reservoir.

With this in mind, at a point along the outlet conduit 29, preferably between the pump 25 and said branch tributaries, such as 30, I have provided the overflow conduit 32 in communication with said outlet conduit.

Said overflow conduit leads thru the cover wall 33 of the oil collecting chamber 34, which is positioned upwardly in relation to the gear housing 26. At a medial height along the vertical walls 35 thereof, the drain conduit 36 communicates with the interior of said chamber and leads into the gear housing 26 at the housing inlet 37, a corresponding gear housing outlet 38 being provided to permit oil which enters thru the inlet 37, to escape.

The chamber 34 serves as a temporary storage for oil 39, in which a "head" of oil accumulates during the operation of the engine, which somewhat gradually drains into said gear housing. By this arrangement, during the stopping, starting or faltering of the engine mechanism, oil is thus supplied from said chamber by force of gravity to said gear housing, although under most running operations, the oil is forced thru said chamber by means of hydraulic pressure created by the oil pump 25.

It is also understood, however, that the chamber 34 serves as a cesspool in the bottom of which dirt or foreign particles, unintentionally carried in the oil passing thru same, may settle and be extracted from time to time by removal of the chamber plug 40, which is threaded in at a lower point of said chamber.

As will be understood by those familiar with so called "gear pumps", the gears 17, 18 and 22 will incidentally influence oil thus directed thru said housing in gear pump manner, and while I do not depend upon this to actually boost the circulation of oil thru said housing, it is preferable that the inlet 130

37 and outlet 38 be located in such relation to the said gears, as to operate in accordance with the pumping tendency of same, by which arrangement the normal operation of 5 said gears will at least in no way impede the intended movement of oil thru the housing 26 between the inlet 37 and the outlet 38. With this in mind, I have located the inlet 37 so as to discharge into the departing interception of the cam shaft gear 17 and the accessory drive gear 22. The outlet 10 38 is correspondingly located at the approaching interception of the crank shaft gear 18 and the cam shaft gear 17. As will 15 be understood by those familiar with the art, this arrangement is favorable to the natural pumping tendency of said gears. In furtherance of this plan, I have also provided an inter-communication 41, between 20 the approaching interception of said cam shaft gear and the accessory shaft gear 22; and the departing interception of said crank shaft gear and said cam shaft gear. By this concerted arrangement, oil introduced into 25 the housing 26 may reach the outlet 38 by paths consistent with the pumping action of said gears, or may find its way between the sides of same, and the adjacent side walls of said housing.

30 It is preferable to keep oil thus conveyed thru said housing, under slight hydraulic pressure and for that reason, I have provided a spring operated escape valve 42, which is automatically opened by the out- 35 rush of oil thru said outlet. In this particular example of my invention I have provided a ball valve, similar in operation to a ball type check valve. The valve housing 43 is conveniently formed integrally with 40 the gear housing 26. The ball 44 is disposed within said housing with suitable side clearance. The spring 45 tends to keep said ball in contact with the ball seat 46, in direct opposition to the movement of oil passing 45 from the outlet 38 thru said valve housing. It will therefore be understood that the spring 45 is of such proportions as to allow escapement of oil from the said gear housing in response to the desired pressure within same. In order, however, to vary the 50 working effect of said spring, an adjustable seat is provided for the normally fixed end of same, in the manner of a screw 46, which is threaded thru the valve housing 55 43, against said spring, being thus opposed to the ball seat 46, in relation to said spring, which is tensioned between the ball 44 and the nose of said screw. Said screw is preferably provided with a manually operated 60 head 47, by which arrangement the working tension of said spring may be readily changed as desired, whether the apparatus is in operation or not. A conventional packing gland 48 encircles said screw in conventional manner, and being threaded into

valve housing 43, serves as a means of preventing leaking of oil around said screw and also as a means for substantially locking same against unintentional turning.

Oil which escapes thru the valve 42, as 70 above explained, is directed from same to the oil reservoir 24, by means of the conduit 49, where it is retarded with other oil thus disposed after being pumped to the various lubricated parts of such engine, as 75 understood.

While I have illustrated in a general way, certain instrumentalities which may be employed in carrying my invention into effect, it is evident that many modifications may be 80 made in the various details, without departing from the scope of the appended claims, it being understood that my invention is not restricted to the particular form herein described. 85

I claim as my invention:

1. In explosive engines employing a main gear and a pair of auxiliary gears associated therewith and a substantially oil tight casing to contain same, a means serving to introduce oil into said casing under pressure; an escape valve serving to automatically release such oil as the hydraulic pressure of same reaches a predetermined pressure per square inch, for supplying oil around said gears at a substantially uniform pressure; the oil entrance in said casing from said introducing means being opposite the departing interception of the main and one of said auxiliary gears; and the oil outlet 90 from said casing to said escape valve being opposite the approaching interception of the main gear and the other of said auxiliary gears, whereby the movement of oil thru said casing will be accelerated by the pumping action of said gears. 100

2. In explosive engines embodying a substantially vertically disposed driving gear, a timing gear meshing therewith and in a plane substantially above said driving gear, an additional gear meshing with the timing gear and in a plane substantially above the same, a substantially oil tight casing therefor, and a means for directing oil to the lubricated parts of such engine, said means having an overflow to release the excess oil thus put in motion; a communication from said overflow to said casing serving to convey oil into same; and a restricted passage serving to automatically release such oil from said casing after it is thus used to lubricate and muffle the working noise of said gears, said inlet and outlet being arranged for utilizing the pumping action of said gears for accelerating the circulation of the oil through 115 said casing. 120

3. In explosive engines employing a central gear and a pair of auxiliary gears and a substantially oil tight casing to contain same; a means serving to introduce oil into 130

said casing; a restricted passage serving to automatically release such oil after it has thus been supplied around said gears; an oil entrance in said casing from said introducing means at the departing interception of the central gear and one of said auxiliary gears; and an oil outlet from said casing to said restricted passage at the approaching interception of the central gear and the other of said auxiliary gears, whereby the movement of oil thus introduced thru said casing is circulated by the pumping action of said gears.

4. In explosive engines embodying a central gear and a pair of auxiliary gears meshing therewith, a substantially oil tight casing therefor, an oil pump means for directing oil to the lubricated parts of such engine, said pump means having an overflow to release the excess oil set in motion thereby; a communication from said overflow to said casing at the departing interception of the central gear with one of said auxiliary gears serving to convey oil into said casing, for lubricating said gears, and muffling the running noises thereof; a restricted passage at the approaching interception of the central gear and the other of said auxiliary gears serving to automatically release such oil after it has been thus supplied around said gears; and a passage from an approaching interception of said central gear and one of said auxiliary gears to a departing interception of said central gear and the other of said auxiliary gears, whereby the movement of oil through said casing will be facilitated by the pumping action of said gears.

5. In explosive engines employing timing gears and a substantially oil tight casing to contain same; a means serving to introduce oil into said casing under pressure; an escape valve serving to automatically release such oil as the hydraulic pressure of same reaches a predetermined pressure per square inch, for supplying oil around said gears at a substantially uniform pressure; and a cess-pool means communicated between said introducing means and said casing in which settling accumulate for clearing the oil.

6. In explosive engines employing a crank shaft gear, cam shaft gear and accessory drive gear; and a substantially oil tight cas-

ing to contain same; a means serving to introduce oil into said casing under pressure; an escape valve serving to automatically release such oil as the hydraulic pressure of same reaches a predetermined pressure per square inch, for supplying oil around said gears at a substantially uniform pressure; a means to vary the tension of said escape valve, by which the permitted pressure within said casing is varied as desired; an oil entrance in said casing from said introducing means at the departing interception of the cam shaft gear and the accessory drive gear; an oil outlet from said casing to said escape valve at the approaching interception of the crank shaft gear and the cam shaft gear, whereby the movement of oil introduced thru said casing by said introducing means is favorable to the pumping action of said gears; a passage from the approaching interception of the cam shaft gear and accessory drive gear to the departing interception of the crank shaft gear and the cam shaft gear, whereby the movement of oil thus introduced is still more favorable to the pumping action of said gears; and a cess-pool means conduitly disposed between said entrance and said introducing means to receive the settling from such oil, said cess-pool means affording accessibility to said settling for removing same when desired.

7. In explosive engines embodying timing gears, a substantially oil tight casing therefor, and a means for directing oil to the lubricated parts of such engine, said means having an overflow to release the excess oil thus put in motion; a communication from said overflow to said casing serving to convey oil into same; a restricted passage serving to automatically release such oil from said casing after it is thus used to lubricate and muffle the working noise of said gears; a cess-pool means serving to communicate said directing means with said casing, to retain the settling from such oil; and a closable drainage serving to relieve said cess-pool of settling as desired.

In testimony whereof, I have hereunto set my hand on this the 11th day of May, 1926,
A. D.

FRANK J. OAKES.
